Patented July 23, 1918.

UNITED STATES PATENT OFFICE.

GEORGE G. POWERS, OF CHICAGO, ILLINOIS, ASSIGNOR TO UNION WIRE MATTRESS COMPANY, OF CHICAGO, ILLINOIS, A CORPORATION OF ILLINOIS.

BED-SPRING CONSTRUCTION.

1,273,181.

Specification of Letters Patent. Patented July 23, 1918.

Application filed January 10, 1916. Serial No. 71,197.

To all whom it may concern:

Be it known that I, GEORGE G. POWERS, a citizen of the United States, residing at Chicago, in the county of Cook and State 5 of Illinois, have invented certain new and useful Improvements in Bed-Spring Constructions, of which the following is a specification.

My invention pertains to the mounting of mattress frames on bedsteads and the like and has particular reference to constructions of this character wherein the mattress-frame is yieldingly supported. One feature of the present invention resides in an efficient 15 method of supporting mattress-frames in this general way so that they will be cushioned, and it also comprises additional means for assisting in maintaining the mattress-frame horizontal and properly positioned 20 both lengthwise and transversely of the bedstead.

In the preferred embodiment of this invention a series of springs are employed for supporting the mattress-frame and another 25 series of centering or supplemental springs are used for assisting in the maintenance of its proper disposition.

In the drawings forming a part of this specification a desirable embodiment of the 30 invention has been depicted and throughout the various views of these drawings like reference characters refer to the same parts.

In the drawing:

Figure 1 is a fragmentary plan view of a 35 corner portion of a bedstead and a mattress-frame supported thereon in the new way;

Fig. 2 is an elevation of the structure of Fig. 1 with the corner-posts of the bedstead omitted; and

Fig. 3 is a side elevation of the same structure as viewed from the right in Fig. 1.

Inasmuch as the constructions at all four corners of the bedstead are the same or reversals of one another, an understanding of 45 one of these will suffice.

The bedstead comprises besides other parts, the usual upright corner-posts 10 and the ordinary detachable side-rails or bars 11, on which the mattress-frame is yieldingly

mounted. Across each end portion of the 50 bedstead and resting upon the bedstead side-rails 11 is a cross-bar 12 composed of a central, tubular portion 13 equipped at each end with a casting 14 having a flat bottom face adapted to rest on the bedstead side-rail, as shown in Figs. 1 and 2.

The mattress-frame includes tubular side-rails 15, each supplied at each end with an open casting 16 projecting both above and below the side-rail and accommodating one of the cross-bars 12. Each member 16 has a socket 16^a receiving the end of the side-rail 15 and in which it is prevented from movement by a pin 16^b. The top ends of these end pieces or castings are connected together by the usual angle-bars 17, which carry the mattress-fabric 18 by means of the customary helical springs 19.

Each member 16 is supported from one of the cross-bars 12 by means of a coil-spring 20 connected to a loop or eye 21 on the cross-bar and to an ear 22 in the lower portion of the casting, each of these springs 20, as is indicated in the various figures, being inclined both transversely and longitudinally of the bedstead and mattress-frames.

In order to hold the mattress-frame more efficiently in proper position and to prevent its swaying and undue tipping when unevenly loaded, the upper portion of each casting 16 is supplied with a lug 23 which is connected by a restraining coil-spring 24 to an eye or loop 25 secured to one of the cross-bars opposite the eye or loop 20. Obviously these four upper springs 24 are inclined both transversely and lengthwise the mattress-frame and assist in preventing cross or longitudinally displacement thereof.

The weight of the mattress-frame, its fabric, and the occupants, is borne by the four springs 20, which expand under the weight imposed upon them, and, due to their opposite inclinations, they tend to hold the mattress-frame centrally with reference to the bedstead-frame. They are assisted in this work, however, by the supplemental or secondary centralizing or counter-balancing springs 24, which act not only to hold the

mattress-frame centrally in position, but also tend to maintain its horizontal disposition when the fabric is unevenly loaded, and to prevent excessive swaying or oscillation.

5 To those skilled in this art, it will be understood that the invention is not limited to the exact features of construction shown, because these may be modified within comparatively wide limits without sacrificing 10 any of the benefits accruing from the use of the invention.

I claim:

1. In a construction of the character described, the combination of a mattress-frame, supporting means adapted to rest on a bedstead-frame, yielding means supporting such mattress-frame from said supporting-means, and supplemental centralizing yielding means connecting said mattress-frame and supporting-means, substantially as described.

2. In a construction of the character described, the combination of a mattress-frame, supporting means adapted to rest on a bedstead-frame, springs supporting said mattress-frame from said supporting-means, and centralizing springs connecting said mattress-frame and supporting-means, substantially as described.

3. In a construction of the character described, the combination of a mattress-frame, supporting means adapted to rest on a bedstead-frame, springs supporting the four corners of said mattress-frame from said supporting-means, and centralizing springs connecting the four corners of the mattress-frame and said supporting-means, substantially as described.

4. In a construction of the character described, the combination of a mattress-frame, supporting-means adapted to rest on a bedstead-frame, inclined springs constituting the sole supports for the mattress-frame supporting said mattress-frame from said supporting-means, and centralizing springs connecting said mattress-frame and supporting-means, substantially as described.

5. In a construction of the character described, the combination of a mattress-frame, supporting-means adapted to rest on a bedstead-frame, springs supporting said mattress-frame from said supporting-means and each inclined both longitudinally and transversely of the mattress-frame, and centralizing springs connecting said mattress-frame and supporting-means, substantially as described.

6. In a construction of the character described, the combination of a mattress-frame, supporting-means adapted to rest on a bedstead-frame, yielding-means supporting said mattress-frame from said supporting-means, and centralizing springs connect-

ing said mattress-frame and supporting-means and inclined transversely of the mattress-frame, substantially as described.

7. In a construction of the character described, the combination of a mattress-frame, supporting-means adapted to rest on a bedstead-frame, yielding means supporting said mattress-frame from said supporting-means, and centralizing springs connecting said mattress-frame and supporting-means and inclined longitudinally of the mattress-frame, substantially as described.

8. In a construction of the character described, the combination of a mattress-frame, supporting-means adapted to rest on a bedstead-frame, yielding-means supporting said mattress-frame from said supporting-means, and centralizing springs connecting said mattress-frame and supporting means and each inclined both longitudinally and transversely of the mattress-frame, substantially as described.

9. In a construction of the character described, the combination of a mattress-frame, supporting-means adapted to rest on a bedstead-frame, springs constituting the sole supports for the mattress-frame supporting said mattress-frame from said supporting means and each inclined both longitudinally and transversely of the mattress-frame, and centralizing-springs connecting said mattress-frame and supporting means and each inclined both longitudinally and transversely of the mattress-frame, substantially as described.

10. In a construction of the character described, the combination of a mattress-frame, supporting-means adapted to rest on a bedstead-frame, mattress-frame supporting springs connected at their upper ends to said supporting means and at their lower ends to said mattress-frame, and restraining springs connected at their upper ends to said mattress-frame and at their lower ends to said supporting-means, substantially as described.

11. In a construction of the character described, the combination of a mattress-frame, supporting-means adapted to rest on a bedstead-frame, yielding-means supporting said mattress-frame from said supporting-means, and a restraining spring at each corner of the mattress-frame having its upper end connected to the mattress-frame and its lower end connected to said supporting-means, each of said restraining springs being inclined upwardly and outwardly both longitudinally and transversely of the mattress-frame, substantially as described.

12. In a construction of the character described, the combination of a mattress-frame, supporting means adapted to rest on

a bedstead frame, a mattress-frame supporting-spring at each corner of the mattress-frame connected at its upper end to said supporting-means and at its lower end to said mattress-frame, each of said springs being downwardly inclined inwardly longi-

tudinally of the mattress-frame and downwardly inclined outwardly transversely of the mattress-frame, and restraining means acting on the mattress-frame, substantially as described.

GEORGE G. POWERS.
